(57) **CLAIM**

The ornamental design for a double wide audio/video stand for a corner, as shown and described.

DESCRIPTION

FIG. 1 is a perspective view of a double wide audio/video stand for a corner showing my new design;
FIG. 2 is a front elevational view thereof;
FIG. 3 is a rear elevational view thereof;
FIG. 4 is a right side view thereof, the left side view being a mirror image;
FIG. 5 is a top view thereof; and,
FIG. 6 is a bottom view thereof.
